ORNAMENT FOR JEWELRY OR THE LIKE

Harold W. Jackson, Pleasant Ridge, Mich., assignor to Chrysler Corporation, Highland Park, Mich., a corporation of Delaware

Application December 22, 1954, Serial No. 33,651

Term of patent 14 years

(Cl. D45—1)

Fig. 1 is a plan view of an ornament for jewelry or the like showing my new design;

Fig. 2 is a front elevational view thereof;

Fig. 3 is a side elevational view thereof; and

Figs. 4, 5 and 6, respectively, are sectional views taken on the lines 4—4, 5—5 and 6—6 of Fig. 1.

I claim:

The ornamental design for an ornament for jewelry or the like, substantially as shown.
